UNITED STATES PATENT OFFICE.

CALVIN W. WILSON, OF WINCHESTER, INDIANA.

LIQUID-LEVEL INDICATOR.

Application filed October 15, 1921. Serial No. 507,845.

To all whom it may concern:

Be it known that I, CALVIN W. WILSON, a citizen of the United States, residing in the city of Winchester, in the county of Randolph, State of Indiana, have invented a new and useful Liquid-Level Indicator, of which the following is a full, clear, and comprehensive specification and exposition, the same being such as will enable others to 10 make and use the same with exactitude.

The object of my present invention, broadly stated, is to provide a gasoline gage which will be strong and durable in construction, easily operated and controlled, 15 efficient and practical in operation, and which can be manufactured and sold at a comparative low price.

More specifically stated,—my object is to provide a gasoline gage especially intended 20 for use when filling large tanks, such as “tank wagons” or “tank trucks” in which gasoline is transported from place to place, the device being self-contained, and to be connected in operative position only when 25 a tank is being filled.

Other minor objects and particular advantages of the invention will suggest themselves in the course of the following specification and as set forth in the appended 30 claims.

The preferred means for carrying out my invention in a practical manner is shown in the accompanying drawings, in which—Figure 1 is a side elevation of my device 35 complete and in operative position in connection with a tank which is shown in cross section. Figure 2 is a central vertical section of my construction. Figure 3 is a top plan view of the same. And Figure 4 is a 40 front elevation thereof.

Similar indices denote like parts throughout the several views.

In order that the construction, the operation, and the advantages of my invention 45 may be more fully understood and appreciated, I will now take up a detailed description thereof in which I will set forth the same as fully and as comprehensively as I may.

Referring now to the drawings in detail: 50 Letter A denotes a tank in cross-section, however, in order to economize space on the

drawings the tank is shown much smaller with relation to the invention than it will be in actual practice. 55

Letter B denotes a filling aperture, which is surrounded by the collar C whereby the aperture B may be closed, when desired, by means of a cap or plug, not shown.

The invention proper comprises a sheet-metal tubular body 1, the same being open at both ends to allow unobstructed passage therethrough, for the purposes hereinafter set forth. 60

Adjustably secured to the exterior of the body 1 is the support 2, the same being secured parallel with the body by means of the bolts 3, the latter being located in slots formed through the body 1, as is shown in Fig. 2, in order to make it adjustable. 65

The support 2 projects above the upper end of the body 1, and extending directly back horizontally from the upper end thereof, and formed integral therewith, is the main-arm 4. 70

Numeral 5 denotes the sector, which is in the nature of a half-circle bar. The rear or outer end portion of the arm 4 is secured to the center of the sector 5 by means of the screw 6, which screw may be locked by 75 means of the lock-nut 7.

Numerals 8 and 9 denote the other adjusting screws, they being threaded vertically through the end portions of the sector 5, and each is adapted to be locked by means of 80 the respective lock-nuts 10 and 11.

Numeral 12 denotes the measuring arm which has a foot 13 formed integral therewith and at right angles thereto and extending back from its lower end and resting 85 on the main-arm 4 where it is secured by the bolts 14. The measuring-arm 12 extends directly upward, but it is located slightly further rearward than is the support 2, as shown in Figs. 1 and 2. 90

Contacting with the underside of the arm 4 and secured thereto by the said bolts 14 is the angular guard 15 whose front portion extends downward in alinement with the arm 12, as shown.

Numeral 16 denotes a float which is located inside the body 1 being concentric with and slidable on the guide-rod 17. 100

The ends of said rods 17 extend out at

right-angles and they are secured to the body 1, as by the nuts 18, whereby the rod 17 is retained in suspension in the center of the body 1 as shown.

5 At the lower portion of the rod 17 there is a cushion 19 on which the float 16 may rest, as shown in Fig. 2.

Secured to one side of the float 16 is the arm 20 to which is secured the lower end of 10 the indicator wire 21 which extends upward between the downwardly extending portion of the guard 15 and the support 2, through an aperture 22 in the arm 4 to the movable indicator 23 to which its upper end is attached.

A retaining wire 24 extends from the ends of the indicator around the arm 12, but 20 slideable thereon, whereby the indicator may slide up and down on the arm 12 as the float raises and lowers.

The face of the arm 12 is graduated, as indicated by the marks 25 to denote gallons or other amounts, each indicated by a number arranged progressively from the lower 25 end upward as shown.

The aperture 26 provides means whereby the device may be suspended when it is not in use.

Operation: In filling the tank A the 30 nozzle of the filling hose is inserted through the aperture B and then the attendant operates a pump located at a little distance from the tank, but it is usually in such position that it is impossible for the operator to determine the depth of the gasoline in the 35 tank without discontinuing the pumping and then looking into the tank, but with this invention the operator may know at all times even at a distance, the precise height 40 of the gasoline in the tank.

To use the device the cap is first removed from the tank, after which the device is inserted, bringing the vertical portion of the guard 15 into contact with the collar C, 45 after which the screws 6, 8 and 9 should be adjusted up or down in order to level the sector 5, and therefore place the body 1 in vertical position.

It is now evident that when the tank is 50 being filled that the float 16 will be lifted from its seat and moved gradually upward, thereby causing the indicator 23 to denote

the amount of fluid in the tank at any time. After the tank has been filled then the device may be removed and the opening in the tank 55 can then be closed, and the device may be preserved for future use.

I desire that it be understood that various changes may be made in the several details of construction and operation without departing from the spirit of the invention and without sacrificing any of the advantages thereof which are new and useful.

Having now fully shown and described my invention, what I claim and desire to 65 secure by Letters Patent of the United States, is—

1. A liquid level indicator comprising a tubular body, a supporting-bar adjustably attached to said body and extending there- 70 above, a main arm extending back from the upper end of the support, a sector attached to said arm, leveling screws carried by the sector, a measuring arm extending up from said main arm, a float located inside the tub- 75 ular body, a guide rod on which said float is mounted, an indicator slideable on the face of the measuring arm, and a wire connecting the indicator with the float, substantially as shown. 80

2. A liquid level indicator comprising a tubular body having an unobstructed passage-way therethrough, a support adjustably secured to the exterior of the body and parallel therewith and extending there- 85 above, a main arm extending back from the upper end of the support, a sector carried by said arm, a measuring-arm extending upward slightly rearward of said support and parallel therewith, means for guiding said 90 measuring-arm, a float located inside the body, a guide rod on which the float is slideable, an indicator slideable on the face of the measuring arm, and means for connecting the indicator with the float, all substantially 95 as shown and described.

In testimony whereof I have hereunto subscribed my name to this specification in the presence of two subscribing witnesses.

CALVIN W. WILSON.
